US00D955370S

(12) **United States Design Patent** (10) **Patent No.:** **US D955,370 S**
(45) **Date of Patent:** **** Jun. 21, 2022**

(54) **EARTIP**

(71) Applicant: **LG ELECTRONICS INC.**, Seoul (KR)

(72) Inventor: **Changwuk An**, Seoul (KR)

(73) Assignee: **LG ELECTRONICS INC.**, Seoul (KR)

(**) Term: **15 Years**

(21) Appl. No.: **35/510,868**

(22) Filed: **Nov. 16, 2020**

(80) **Hague Agreement Data**

Int. Filing Date: **Nov. 16, 2020**

Int. Reg. No.: **DM/211405**

Int. Reg. Date: **Nov. 16, 2020**

Int. Reg. Pub. Date: **Dec. 4, 2020**

(30) **Foreign Application Priority Data**

Jul. 22, 2020 (KR) 30-2020-0033912

(51) **LOC (13) Cl.** **14-01**

(52) **U.S. Cl.**

USPC **D14/223**

(58) **Field of Classification Search**

USPC D14/192, 205, 206, 223, 372; D24/106, D24/174

CPC G10K 11/1781; G10K 2210/1081; H04R 2420/07; H04R 1/083; H04M 1/6066

See application file for complete search history.
